(57) **CLAIM**

The ornamental design for an all weather dispenser as shown and described.

DESCRIPTION

FIG. 1 is a perspective view of an all weather dispenser of the new design;

FIG. 2 is another prospective view of the all weather dispenser of FIG. 1;

FIG. 3 is a front elevational view of the all weather dispenser of FIG. 1;

FIG. 4 is a right side elevational view of the all weather dispenser of FIG. 1;

FIG. 5 a top plan view of the all weather dispenser of FIG. 1;

FIG. 6 is a bottom view of the all weather dispenser of FIG. 1; and,

FIG. 7 is a rear elevational view of the all weather dispenser of FIG. 1.

The broken lines shown in the figures represent portions of the all weather dispenser that form no part of the claimed design.

1 Claim, 6 Drawing Sheets
